CLAIM

The ornamental design for a snack tray, as shown and described.

DESCRIPTION

FIG. 1 is a top perspective view of a snack tray.
FIG. 2 is a top view of the snack tray shown in FIG. 1.
FIG. 3 is a bottom view of the snack tray shown in FIG. 1.
FIG. 4 is a right side view of the snack tray shown in FIG. 1.
FIG. 5 is a left side view of the snack tray shown in FIG. 1.
FIG. 6 is a rear view of the snack tray shown in FIG. 1.
FIG. 7 is a front view of the snack tray shown in FIG. 1.
FIG. 8 is a top perspective view of a snack tray.
FIG. 9 is a top view of the snack tray shown in FIG. 8.
FIG. 10 is a bottom view of the snack tray shown in FIG. 8.
FIG. 11 is a right side view of the snack tray shown in FIG. 8.
FIG. 12 is a left side view of the snack tray shown in FIG. 8.
FIG. 13 is a rear view of the snack tray shown in FIG. 8.
FIG. 14 is a front view of the snack tray shown in FIG. 8.
FIG. 15 is a top perspective view of a snack tray.
FIG. 16 is a top view of the snack tray shown in FIG. 15.

FIG. 17 is a bottom view of the snack tray shown in FIG. 15.
FIG. 18 is a right side view of the snack tray shown in FIG. 15.

FIG. 19 is a left side view of the snack tray shown in FIG. 15.

FIG. 20 is a rear view of the snack tray shown in FIG. 15.
FIG. 21 is a front view of the snack tray shown in FIG. 15.
FIG. 22 is a top perspective view of a snack tray.

FIG. 23 is a top view of the snack tray shown in FIG. 22.

FIG. 24 is a bottom view of the snack tray shown in FIG. 22.

FIG. 25 is a right side view of the snack tray shown in FIG. 22.

FIG. 26 is a left side view of the snack tray shown in FIG. 22.

FIG. 27 is a rear view of the snack tray shown in FIG. 22; and,

FIG. 28 is a front view of the snack tray shown in FIG. 22.
The broken lines having equal segments represent portions of the article that form no part of the claimed design. The broken lines having unequal length segments illustrate the boundaries between claimed and unclaimed portions of the design and form no part of the claimed design.

Any line in a drawing may provide a boundary line of a claimed design element. A boundary line of a claimed design element may also be defined in an area between lines in a drawing. An element or a subset of any combination of elements in a drawing may form a claimed design.
